COMBINED BAR AND SUPPORT FOR A TELEVISION SET

Missionary E. Flemings, 2811 Clayton St.,
Denver, Colo. 80205

Filed July 15, 1971, Ser. No. 163,137

Term of patent 14 years

Int. Cl. D6—04

U.S. Cl. D6—144

FIG. 1 is a perspective view of a combined bar and support for a television set showing my new design;

FIG. 2 is a top view thereof;

FIG. 3 is a front view thereof;

FIG. 4 is a side view thereof; and

FIG. 5 is a back view thereof.

I claim:

The ornamental design for a combined bar and support for a television set, as shown.
